LAMP SHADE

Gerald E. Thurston, Cranford, N.J., assignor to Lightolier
Incorporated, a corporation of New York

Filed Mar. 30, 1961, Ser. No. 64,555

Term of patent 7 years

(Cl. D48—16)

FIG. 1 is a perspective view of the lamp shade showing my new design taken from the top thereof,

FIG. 2 is a view similar to FIG. 1 taken from the bottom thereof,

FIG. 3 is a top plan view thereof, and

FIG. 4 is a side elevational view thereof.

I claim:

The ornamental design for a lamp shade, substantially as shown.
